UNITED STATES PATENT OFFICE.

CHARLES J. AHRENFELDT, OF NEW YORK, N. Y.

DESIGN FOR A CUP OR SIMILAR ARTICLE.

SPECIFICATION forming part of Design No. 34,268, dated March 26, 1901.

Application filed December 28, 1900. Serial No. 41,428. Term of patent 7 years.

To all whom it may concern:

Be it known that I, CHARLES J. AHRENFELDT, a citizen of the United States, residing at the city of New York, county of New York, and State of New York, have invented and produced a new and original Design for a Cup or Similar Article, of which the following is a specification, reference being had to the accompanying drawings, forming a part thereof.

In the said drawings, Figure 1 is a side view of a cup, showing my design. Fig. 2 is a bottom view of the same.

The cup is divided into an upper and lower portion A and B, respectively, by the horizontal annular depression D, located near the center thereof. Within this depression is an annular wave-like band of ornamentation C, running around the exterior of the cup and consisting of a series of escalloped ornaments

c, supplemented by acorn-like ornaments c', and delicate straight lines c'', extending upwardly a short distance therefrom.

Vertical depressions E run from the base of the cup up to the depression D, from which point ridges H proceed in the same line to the upper edge. The handle G is slightly fluted and is joined to the cup by leafed ornaments F and F'.

What I claim is—

The design for a cup or similar article substantially as herein shown and described.

Signed at the city of New York, in the county of New York and State of New York, this 14th day of May, 1900.

CHARLES J. AHRENFELDT.
